UNITED STATES PATENT OFFICE

EPHRAIM H. STANTON, OF SAN PABLO, CALIFORNIA

CLOTHESPIN

Application filed April 5, 1932. Serial No. 603,276.

This invention is a clothes pin and is especially directed to a clothes pin which is adapted to be conveniently attached to, or detached from, a clothes line or a wire, before or after securing the clothes pin to an article of clothing.

The main object of the invention is to provide a clothes pin which may be attached to an article of clothing following which the clothes pin may be readily attached to a clothes line without any loosening of the gripping element on the article of clothing.

Another object of the invention is to provide resilient gripping means at the handle end of the clothes pin by which the clothes pin is readily attached to a line.

A further object of the invention is to provide a special gripping element which is readily assembled on the standard clothes pin by means of which the above objects may be accomplished.

Other objects and advantages of the invention will become apparent as the following description is read on the drawing forming a part of this specification, and in which similar reference characters are used to designate similar parts throughout the several views, of which:

Fig. 1 is a side view of the preferred form of my invention.

Fig. 2 is a transverse view of Fig. 1.

Fig. 3 is a transverse view of the resilient clothes line gripping means and which is adaptable for use with standard clothes pins.

Fig. 4 is a modification of the invention.

Fig. 5 is a side view of another modification of the invention.

Fig. 6 is a transverse view of Fig. 5.

Fig. 7 is a view showing the method of using the clothes pins.

The invention consists of a specially formed resilient element having the legs 10 and 11 having inturned ends 12 which are adapted to cooperate with the spring eye 13 of a standard clothes pin, the other end of this element having retractions 14 which fit about the handle members 15 so as to retain the element in position on the handle member. The legs 10 and 11 have an arcuately formed recess 16 which is adapted to fit about a

clothes line or wire and extending upwardly in diagonal relation as shown at 17 providing a guide for the line.

This element may be formed integral with the spring 18 if so desired, the clothes pin consisting of the usual gripper elements 19 and 20 each having a semi-recess 21, which may readily be replaced with the serrated faces 22 as shown in Fig. 4, as these clothes pins are not normally intended to be secured to the line by means of the gripper elements. The modification shown in Fig. 4 consists of a spring element the portion 23 of which is shaped similarly to the portion 16-17 of Fig. 1, and which also straddles the handle portion 15 continuing backwardly and being retained by a recess 24, the spring passed about the handle member 15.

Another modification of the invention is shown in Figs. 5 and 6 in which the attaching element is made integral with one of the handle members and consists of two projecting plates 25 and 26 which are provided on their inner edges with recesses 27, the line 28 being secured between one of the handle members 15 and the plates 25 and 26.

In Fig. 7 the method of using these clothes pins is clearly illustrated in which the article of clothing 29 has first had the clothes pins attached by means of the gripper portion of the clothes pin after which the clothes pins are attached to the line 28.

It will be noted that with an article of clothing attached by means of the gripper portion that the application of the upper portion of the clothes pin to a line has no tendency to release the article of clothing, instead gripping the article more firmly. Also that the spring 18 effectively forms a cooperating part of the invention as its resiliency is transmitted to the upper portion of the handle, causing the handle to resiliently secure the line in the recesses 16 or 27.

An upward pressure against the line as indicated at 30 will tend to force the handles 15 apart against the action of spring 18 and as soon as the line drops into the recess 16 or 27 the handles 15 are retracted by the spring 18 thereby firmly gripping the line.

If it is desired to permanently secure the

clothes pin on the line, the form of resilient element indicated in Fig. 4 is preferred as the clothes line can be slipped past the terminal 31, in which case the element would 5 act as a hook, the clothes line being disposed as indicated at 32.

This clothes pin has many other uses in addition to that of hanging a washing on the line and it is peculiarly adapted for use with 10 certain types of coat hangers, for suspending pictures and for many other uses which will readily be made manifest to the user of the device.

Having described an operative device, it 15 will be understood that variations in construction and arrangement of parts which are consistent with the appended claims may be resorted to without detracting from the spirit or scope of the invention or sacrificing 20 any of the advantages thereof.

I claim:

1. In combination with a clothes pin, a pair of spanning elements secured to one handle of the clothes pin and having recesses 25 formed which are adapted to coact with the other handle for gripping a clothes line therebetween.

2. A suspending element for clothes pins adapted to secure the clothes pin to a clothes 30 line comprising a member secured to one handle of the clothes pin and having recesses formed in opposition to the other handle of the clothes pin and being secured in the spring eye of said clothes pin whereby a line 35 may be removably secured within the recess in cooperation with the other handle.

3. In combination with a pair of opposed clothes pin members, each member comprising a gripper portion and a handle portion 40 and a spring securing said members together and forming coincidentally a pivot for said members; means secured to one handle portion and adapted to cooperate with the other handle portion for removably securing a 45 clothes line therebetween, said means and said other handle portion being resiliently urged by said spring to secure the clothes line therebetween.

4. In combination with a clothes pin comprising 50 two members resiliently urged together, each member consisting of a gripper portion and a handle portion: line gripping means interposed relative to said handle portions and mounted on one handle portion in 55 cooperative relation to the other handle portion.

In testimony whereof I affix my signature.
EPHRAIM H. STANTON.
